R. T. WHIPPLE

AUTOMATIC TAKE-UP FOR BRAKE BANDS

Filed Oct. 21, 1922

Inventor.

Raymond T. Whipple

Attorney.

Victor J. Evans.

UNITED STATES PATENT OFFICE.

RAYMOND T. WHIPPLE, OF SAN FRANCISCO, CALIFORNIA, ASSIGNOR, BY DIRECT AND MESNE ASSIGNMENTS, TO CHARLES H. BAER, OF SAN FRANCISCO, CALIFORNIA.

AUTOMATIC TAKE-UP FOR BRAKE BANDS.

Application filed October 21, 1922. Serial No. 596,108.

To all whom it may concern:

Be it known that I, RAYMOND T. WHIPPLE, a citizen of the United States, residing at San Francisco, in the county of San Francisco and State of California, have invented new and useful Improvements in Automatic Take-Ups for Brake Bands, of which the following is a specification.

This invention relates to improvements in automatic take-ups for brake bands, and is particularly designed for taking up the band employed in the transmission of a well known type.

The principal object of this invention is to provide an automatic take-up which may be applied to the tightening rod without altering the same.

Another object is to provide means whereby it will be unnecessary to open the gear case for the purpose of making a band adjustment.

A further object is to provide a device of this character which is simple in construction, cheap to manufacture and one which may be marketed at a reasonable price.

Other objects and advantages will be apparent during the course of the following description.

In the accompanying drawings forming a part of this specification, and in which like numerals are employed to designate like parts throughout the same,

Figure 1 is a diagrammatic view of a brake band showing the outline of the gear case in dotted lines.

Figure 2 is a fragmentary detail view partly in cross-section of a brake band.

Figure 3 is a plan view of the tightening 40 ratchet,

Figure 4 is a side elevation of Figure 3,

Figure 5 is a plan view of an intermediate ratchet,

Figure 6 is a side elevation of Figure 5,

Figure 7 is a top plan view of an expansion spring,

Figure 8 is a side elevation of Figure 7,

Figure 9 is a bottom plan view of the band retaining sleeve and its cap,

Figure 10 is a top plan view of the retaining cap,

Figure 11 is a side elevation of Figure 10,

Figure 12 is a bottom plan view of the retaining cap, and

Figure 13 is a side elevation of the retaining sleeve.

The construction of a transmission as shown is such that when it is necessary to adjust one of the brake bands it is necessary to remove the gear case cover and then tighten the end bolt of the compression rod. This is a tedious and very dirty job owing to the fact that these bands receive a discharge of oil thereover when the car is in motion. I therefore propose to apply to the compression rod a self adjusting mechanism which will automatically adjust itself on the compression rod as the brake band wears.

In the accompanying drawings wherein for the purpose of illustration is shown a preferred example of the same, the numeral 14 designates the usual brake band mounted upon the brake drum, shown in dotted lines at 16, of a well known transmission which is mounted within a housing 17, also shown in dotted lines. A compression rod 18 passes through the upturned ends 19 and 21 of the brake band 14 and extends outwardly therefrom through the side of the housing and is secured to a brake pedal 22. This brake pedal has its lower portion formed upon an angle as shown at 23, so as to form a cam against the side of the housing, which is also formed upon an incline as shown at 24, the result being that as the pedal 22 is moved about its pivot point, these inclined surfaces 23 and 24 cause the compression rod 18 to move in the direction of the arrow a. As the upturned end 21 of the band 14 is held stationary, the result is that the upturned end 19 is moved toward the upturned 21, thereby contracting the band about its brake drum. An expansion spring 26 is coiled about the compression rod 18 and abuts the two upturned ends of the band, 19 and 21. The construction thus far described is the ordinary construction employed.

My invention relates to the applying of a retaining sleeve 27 to the threaded end 28 of the compression rod 18. This retaining sleeve is slipped upon the compression rod 18 so that it abuts the upturned end 19, and

- is further provided with flat faces as shown at 29 and 31 which are adapted to lie between the bifurcated portions of the upturned end 19 as shown in dotted lines in Figure 2. This retaining sleeve is provided with ratchet teeth 32, and with a shoulder 33. Recesses as shown at 34 are provided on each side of this nut, the purpose of which will be later seen.
- 10 The numeral 36 refers to an intermediate ratchet having ratchet teeth formed on opposite sides thereof. These teeth are shown at 37 and 38 of Figure 6. This intermediate ratchet 36 is threaded upon the compression rod 18 so as to have its teeth 38 engage the teeth 32 of the retaining sleeve 27. At 39, I have shown a tightening ratchet, the construction of which is best shown in Figures 3 and 4. This ratchet is adapted to slip upon the compression rod 18 and is provided with a key 41 which fits within a keyway 42 thus preventing rotation of this ratchet. One face of the ratchet 39 is provided with teeth as shown at 43, which are adapted to contact the teeth 37 of the intermediate ratchet 36. A spring 44 is slipped upon the rod 18 so as to abut the ratchet 39. This spring is held in place through the medium of a cap 46 having spring fingers 47 and 48, which spring fingers are adapted to pass through the recesses 34 of the sleeve 27, after which the cap 46 is given a quarter turn so that these fingers engage the shoulder 33, thus retaining the compression spring in engagement with the ratchet 39.
- 35 The operation of my device is as follows:—
- When the brake pedal 22 is moved to cause compression of the brake, the compression rod 18 turns, which rotary movement is transmitted to the ratchet 39 through its key engagement. This movement is transmitted through the teeth 43 to the teeth 37 of the intermediate ratchet 36. The movement of the intermediate ratchet causes the teeth 38 to ride upon the teeth 32 of the sleeve 27. Should the rotary movement of the compression rod be greater than the width of one of these teeth, the result will be that the intermediate ratchet will move up one tooth with relation to the sleeve 27, and as the pedal is released, the ratchet 39 will move rearwardly with the compression rod and also take a new hold upon the intermediate ratchet 36. As the intermediate ratchet 36 is screw threaded upon the rod 18, it will be seen that every time it is advanced a tooth, it is taking up slightly upon the brake band. If, however, the movement of the 60 brake pedal is not sufficient to take up the

band, the result will be that the teeth 32 and 38 will merely ride upon each other, and again return to the same position.

It will thus be seen that I have provided a very simple mechanism which will automatically adjust the brake band when wear is taking place. It is obvious that this same mechanism may be applied to brakes other than those of the type shown. 65

It is to be understood that the form of my invention herewith shown and described is to be taken as a preferred example of the same, and that various changes in the shape, size and arrangement of parts may be resorted to without departing from the spirit 75 of the invention or the scope of the subjoined claims. 70

Having thus described my invention, I claim:—

1. In a device of the character described, 80 the combination with a compression brake band, a compression rod extending between the ends of said brake band, means for rotating said rod, a sleeve slidably held upon said rod, an intermediate ratchet secured 85 upon the end of said rod so as to contact said sleeve, and a tightening ratchet slidably keyed on said rod, substantially as and for the purpose described.

2. In a device of the character described, 90 the combination with a compression brake band having upturned ends, a compression rod adapted to engage said upturned ends, means for imparting partial rotation to said rod, ratchet means secured to one end of said 95 brake band, an intermediate ratchet threadedly engaged by said rod and adapted to have engagement with said ratchet means, a tightening ratchet slidably keyed to said rod and adapted to contact said intermediate 100 ratchet, and spring means for causing said ratchets to contact one with the other.

3. In a device of the character described, 105 the combination with a compression brake band having upturned ends, a compression rod adapted to engage said upturned ends, means for imparting partial rotation to said rod, ratchet means secured to one end of said 110 brake band, an intermediate ratchet threadedly engaged by said rod and adapted to have engagement with said ratchet means, a tightening ratchet slidably keyed to said rod and adapted to contact said intermediate 115 ratchet, spring means for causing said ratchets to contact one with the other, and a cap adapted to retain said spring in contact with said tightening ratchet.

In testimony whereof I affix my signature.

RAYMOND T. WHIPPLE.
